ATTORNEYS,

UNITED STATES PATENT OFFICE.

JOHN FEGGETTER BLAKE, OF NEW HAVEN, CONNECTICUT.

ELECTRIC PUMP-MOTOR.

SPECIFICATION forming part of Letters Patent No. 520,722, dated May 29, 1894.

Application filed September 7, 1893. Serial No. 484,998. (No model.)

To all whom it may concern:

Be it known that I, JOHN FEGGETTER BLAKE, a citizen of the United States, residing at New Haven, in the county of New Haven and State 5 of Connecticut, have invented new and useful Improvements in Electric Pump-Motors, of which the following is a specification.

This invention relates to an electric motor for pumping air into beer barrels and receptacles for generating pressure whereby the contents of the receptacle can be raised to a higher level than that occupied by the receptacle and the invention consists in the novel features pointed out in the following specification and claims and illustrated in the annexed drawings, in which—

Figure 1 is a side elevation of the motor applied to a barrel, the motor being sectioned along $x x$ Fig. 2. Fig. 2 is a section along $y y$ 20 Fig. 1. Fig. 3 is a section along $z z$ Fig. 2. Fig. 4 is a detail view of a cylinder.

In the drawings the letter A indicates a cask or receptacle the beer or contents from which are forced up by the pressure in the 25 cask through pipe B to be tapped off at the cock C as required. The air for generating the required pressure is forced through pipe D into the cask. The pipe D connects with pump cylinder E in any well known way, the 30 plunger F in cylinder E being actuated by the pitman G connected to crank pin H on pulley I driven by belt K and pulley L, which latter is actuated by an electric motor M of any suitable well known construction and 35 having the requisite power for generating the required air pressure.

Connected to the pressure pipe D is a pressure chamber N and when the pressure in cask A sinks below the required degree the diaphragm O in pressure chamber N will drop or collapse so as to allow the stem P resting 40 on diaphragm O to sink and the lever Q pivoted at Q', and resting on stem P, is drawn down by spring R connected to fixed arm S 45 by a nut T. By screwing the nut T one way or another the spring R can be loosened or tightened so as to draw down the lever Q on a less or greater diminution of pressure in chamber N as required. The lever Q connects 50 by link U with the lever V W fulcrumed at X and having a roller Y which when the lever arm V is depressed will ride from below

the shoulder a of spring Z a and come to rest in the hollow or bend Z of said spring. The lever arm V being depressed will depress the 55 arm b of lever b c fulcrumed at d so as to cause the roller e on said lever arm b to ride from above the shoulder f of spring f g into the hollow or bend g of said spring. This motion of lever b c will bring the contact 60 piece h on lever arm c into touch with the contacts i connected to conductors k thereby closing the circuit and starting the motor M to pump air into cask A.

When the pressure in cask A has risen to 65 the required degree the diaphragm O in chamber N will raise lever Q against the resistance of spring R so as to raise lever arm V and depress lever arm W, bringing roller Y below the bend a of spring Z a. The lever arm 70 W being depressed will depress lever arm c so as to break the contact between the piece h and contacts i, thereby stopping the motor. When the lever arm c is depressed the lever arm b rises so as to carry roller e up above 75 bend f of the spring f g. The springs Z a and f g thus prevent accidental movement of the levers V W and b c. These springs Z a and f g also cause the levers V W and b c to jump 80 quickly from one position to another, thereby moving the contact piece h rapidly into and out of connection to avoid the formation of an arc. I have also found it of advantage to connect the link U to lever V W by a slotted connection l (Fig. 2) so that the spring Z a can 85 throw or snap the lever V W to some extent independently of link U.

The air enters into pipe D through the well known alternating pump valves m m (Fig. 1) one valve closing as the other opens as well 90 known. I have found it of advantage also to place entrance holes n (Fig. 4) near one end of the pump cylinder E, the piston F when near its back stroke passing slightly beyond these holes n and allowing air to enter said 95 holes to thoroughly fill the cylinder E, so that on the forward or pumping stroke of piston or plunger F a full charge of air will be forced from cylinder E into pipe D.

The operation of the device it is noticed is 100 automatic, the motor starting when the air pressure sinks below the required degree and stopping when the pressure is of sufficient intensity.

What I claim as new, and desire to secure by Letters Patent, is—

1. The combination with a cask or receptacle, and a pump for supplying air pressure to the cask, of a pressure chamber containing a flexible diaphragm which is moved by an increase or a reduction of pressure in the cask or receptacle, a movable stem acted upon by the diaphragm, a contact lever *b c*, a transmission lever *V W*, and connecting devices between the said movable stem and the transmission lever, substantially as and for the purposes described.
2. The combination with a cask or receptacle and a pump for supplying air pressure to the cask of a pressure chamber, a contact lever as *b c*, a transmission lever as *V W* actuated by the pressure in the chamber and made to actuate the contact lever, springs or detents for said levers, and an electric motor actuated through said contact lever and made

to actuate the pump substantially as described.

3. The combination with a cask or receptacle and a pump for supplying air pressure to the cask, of a pressure chamber, an actuating lever as *Q*, actuated by the pressure in the chamber, a regulating spring as *R* for the actuating lever, a transmission lever connected to the actuating lever a contact lever actuated by the transmission lever, and an electric motor actuated through said contact lever and made to actuate the pump substantially as described.

In testimony whereof I have hereunto set 35 my hand in the presence of two subscribing witnesses.

JOHN FEGGETTER BLAKE.
